TOY DUMP TRUCK

Louis G. Muys and Albert G. Keller, Chicago, Ill.,
assignors to Strombecker Corporation

Filed June 29, 1970, Ser. No. 23,739

Term of patent 14 years

Int. Cl. D21—01

U.S. Cl. D34—15

Fig. 1

Fig. 2

Fig. 3

Fig. 4

Fig. 5

FIG. 1 is a perspective view of a toy dump truck embodying our ornamental design;

FIG. 2 is a side elevational view of the toy dump truck of FIG. 1;

FIG. 3 is a front elevational view of the toy dump truck of FIG. 1;

FIG. 4 is a plan view of the toy dump truck of FIG. 1; and

FIG. 5 is a rear elevational view of the toy dump truck of FIG. 1.

We claim:

The ornamental design for a toy dump truck, as shown.
